FACE PLATE FOR SURROUNDING THE DIAL OF AN INTERNATIONAL TIME CLOCK

**Tancredi E. De Lorenzo, 20000 Woodside,
Harper Woods, Mich. 48225**

Filed July 29, 1974, Ser. No. 492,449

Term of patent 14 years

Int. Cl. D10—07

U.S. Cl. D10—123

The figure is a front elevational view of a face plate for surrounding the dial of an international time clock showing my new design, the plate being of no appreciable thickness and plain and unornamented, the rear surfaces not shown.

I claim:

The ornamental design for a face plate for surrounding the dial of an international time clock, as shown and described.
